UNITED STATES PATENT OFFICE.

MARSHALL F. CUMMINGS, OF NASHUA, NEW HAMPSHIRE, AND NATHAN G. LAPHAM, OF CHELMSFORD, MASSACHUSETTS, ASSIGNEES TO T. C. ENTWISTLE COMPANY, OF LOWELL, MASSACHUSETTS, A CORPORATION OF MASSACHUSETTS.

PNEUMATIC LINT CLEARER FOR WARPING MACHINES.

Application filed March 1, 1924. Serial No. 696,188.

To all whom it may concern:

Be it known that we, MARSHALL F. CUMMINGS and NATHAN G. LAPHAM, citizens of the United States, residing at Nashua, in the 5 county of Hillsborough, State of New Hampshire, and at Chelmsford, county of Middlesex, Commonwealth of Massachusetts, have invented a certain new and useful Improvement in Pneumatic Lint Clearers for Warping Machines, of which the following is a specification, reference being had therein to the accompanying drawings.

The invention is applicable to warping machines, looms and the like, and has relation to the class of devices or appliances 15 which have been devised for employment in such machines to effect the removal of the lint that separates from the yarns or threads that are operated upon therein.

20 The invention is more especially an improvement upon the pneumatic lint-clearer devices that are shown and described in former United States Letters Patent No. 1,339,182 granted under date of May 4, 1920, 25 and No. 1,447,418 granted under date of March 6, 1923.

The invention has for its general object 30 to provide improved lint-clearer devices of simpler and less expensive design and construction than prior devices of this nature, designed for use in connection with warping machines, looms, and other machines in which a series of traveling yarns or threads arranged side by side in the manner of a 35 warp are operated upon. A special object of the invention is to enable a manual shift of the blower from the position occupied by it at a given moment, as for instance during stoppage of the machine, to be effected so as 40 to facilitate access to yarns or threads immediately below the blower while in the said position. The travelling blower of lint-clearer devices embodying the present invention is traversed by an endless belt, preferably disposed above the series of yarns or 45 threads. In the more complete embodiment of the features of the invention, the blower is combined with the said belt by connecting means permitting shift of the blower independently of the belt, and relative to the 50 latter, so as to remove the blower from over the yarns or threads, which may be directly

under it, more particularly when the mechanism stands at rest.

The drawings represent an illustrative embodiment of the invention in connection with a warping machine. 55

In the drawings,—

Fig. 1 is a front elevation of the said warping machine and illustrative embodiment. 60

Fig. 2 is a view in vertical section in the plane of the dotted line 2—2 of Fig. 1.

Fig. 3 is a view in section on the dotted lines 3—3 of Fig. 1, with portions broken 65 away, showing on a larger scale than Figs. 1 and 2 the fan-blower and the parts more immediately associated therewith.

Fig. 4 is a front view on a larger scale, partly sectional, showing the fan-blower and 70 its oscillating and traversing mechanisms.

Fig. 5 is a partly sectional detail view showing a modified driving arrangement.

Figs. 1 and 2 of the drawings represent a typical warping machine, and the preferred 75 arrangement of the improved lint-clearer devices in connection therewith.

In Fig. 2 yarns or threads 1 are represented as extending (from a warper-creel, not shown) through the back comb 2, over 80 the measuring roll 3, under the movable falling rod 4, over the supporting roll 5, through the front comb 6, over the front supporting roll 7, to the warper beam 8, on which latter they are wound by the action of the machine. 85 Drop-wires 9, 9, are represented as hung in usual manner upon the yarns or threads at points between the rear supporting roll 5 and the front comb 6.

As in the machines of the earlier Letters 90 Patent aforesaid, the blower of the lint-clearer devices is shown applied and arranged to operate to blow away lint which separates from the yarns or threads during their passage from rear to front in the machine, and so as to keep the back and front combs, drop-wires, and other parts adjacent the drop-wires, clear and free from lint. 95

In this embodiment of the invention suitable stands or uprights 10, 10, erected above 100 the bed of the warping machine support a track 11, which in practice may be of any construction suitable for the form of carriage or trolley employed. Upon said track

travels a carriage or "trolley" 12, Figs. 3 and 4, which in practice may be of any suitable construction and design. The combination shown clearly in Figs. 3 and 4 comprises a 5 track in the shape of an inverted U, with the lower edges of the sides inturned in the form of curved flanges, and a carriage or trolley provided with pairs of wheels or rollers 120, 120, fixed upon opposite ends of short axles 10 121, 121, which rotate freely in bearings in connection with body-members 122, 122, the said carriage or trolley being entered within the track 11, with the wheels or rollers 120, 120, resting upon and adapted to travel 15 along the inturned flanges, as shown.

With the carriage or trolley 12 is combined the blower by means of which a current of air is sent toward the yarns or threads 1 and the various machine parts at 20 the top of the machine. In this instance, as in the patents aforesaid, the blower is an electric fan 13, which kind of blower is preferred, although the invention is not necessarily restricted in all instances to the employment of a fan-blower. The said fan 13 is shown mounted between the arms of a bail or yoke 14, having at the top thereof a neck or boss which is socketed to fit upon a pin or stud 15 carried by and projecting 25 downward from the body-members 122, 122, of the carriage or trolley 12, the bail or yoke being fixedly attached to the stud or pin 15 by means of the clamping screw 16.

The means employed in accordance with 30 the present invention to traverse the blower across the width of the machine, in order to subject all the yarns or threads of the series, spread out thereon, to the action of the blast, comprises an endless cable or belt 17 extending transversely across the series of yarns or threads, in this instance above the said 35 series, and supported by two pulleys 18, 19, one at each side of the series, each of which pulleys is mounted on an upright revoluble 40 shaft supported in a bearing in connection with a bracket 100 that is made fast to the upright 10 at one side of the machine. The blower is connected with the cable or belt 17 which parallels the track 11, and is 45 driven by means of power applied to one, 20, of the said upright shafts. Fig. 1 shows the power applied to said shaft 20 through a worm 21 and worm-gear 22, from the driving mechanism of the machine, the said 50 worm-gear being secured to the lower end of the said upright shaft 20. If preferred, however, the shaft 20 and pulley 18 may be similarly driven, as shown in Fig. 5, from a short jackshaft 40 mounted in a bearing 41 55 on the adjacent stand 10 and provided with a pulley 42 to which rotation is imparted by a belt 43 from any desired source of power outside the machine, as, for example, an overhead shaft (not shown).

60 Referring to the feature of providing for

shifting the blower manually so as to expose to inspection and convenient access the yarns or threads which at any time may be underneath the same, as for instance in the position in which it stands when the machine is at rest, this manual shifting may be effected by taking hold of the endless cable or belt and causing it to slip around the pulleys 18, 19, taking the blower with it, in one direction or the other as the case may be. 70 Preferably, however, in order to render it unnecessary, ordinarily, to shift the cable or belt itself, we employ a connection between the cable or belt and the blower enabling the blower to be shifted to a convenient extent 75 without movement imparted to the cable or belt. In the present embodiment we employ a link consisting of a flexible connection 24 which may be formed of a piece of material like the cable or belt 17, one end of such link 80 being connected to the blower, as by the ring 250 fitting loosely around the downwardly projecting stud or pin 15, the other end of the link being engaged with some point in the length of the cable or belt 17. By means 85 of this flexible connecting link 24 the carriage and blower are towed back and forth along the track 11, traversing the width of the machine, merely pausing for a moment 90 at each end of its traverse while the end of the flexible connection 24 which is fixed to the cable or belt 17 makes the turn around either of the pulleys 18, 19, in company with such cable, and resumes its traverse in the 95 opposite direction as soon as the slack in the connection 24 is taken up by reason of the continuous travel of the cable 17.

A drawback about the traversing means hitherto employed for traversing the blower across the width of the machine has been 100 that the blower itself has often chanced to stop in such position as to obstruct the work of the attendant of the machine in working upon the yarns, as for the purpose of piecing up broken yarns or threads. The positive 105 connection of the blower with its traversing means in such cases required restarting of the machine to shift the blower out of the attendant's way, which restarting has often been undesirable until after the work of the 110 attendant should have been completed. In the present embodiment, in case the machine should be brought to rest with the blower in the way of the attendant, the carriage and blower may be easily pushed, by hand on 115 beyond the point at which they come to rest, to an extent corresponding with the length of the flexible connection 24, without moving the cable or belt. Various mechanical 120 substitutes may take the place of the flexible 125 connection 24.

As in the Letters Patent aforesaid, to increase the effectiveness of the clearing action of the blast, the blower shown in the drawings is contrived to oscillate in a fore-and- 130

aft direction, parallel to the length of the yarns 1, at the same time that it is traversed across the width of the machine. The provision for such swinging motion is made by 5 providing journals 25, 25, on the casing of the electric fan 13 and mounting them to turn in bearings in connection with the arms of the bail or yoke 14. In this instance, well-known devices are shown for oscillating 10 the fan on its journals automatically, such devices comprising a jackshaft 26 gear-driven by the main fan-shaft and extending outwardly from the fan-casing, and having fixed upon its outer end the disk or plate 27, 15 and a link 29 coupled at one of its ends to a crank-pin 28 borne by the disk 27 and at its other end to a pivot-pin 30 formed upon a suitable member fixed upon the bail or yoke 14, such as an L-headed pin 31 having 20 the attaching portion thereof driven into a hole provided for it in one arm of the bail or yoke. When the fan rotates, the jackshaft 26 rotates also, moving the crank-pin 28 in a circular path with respect to said 25 jackshaft. As the link 29 is pivoted at one end to a member that is fixed with respect to the bail 14, and cannot move in the direction of its length, the travel of the crank-pin 28 to which the other end of said link is attached serves to turn the fan back and forth upon its journals 25, 25, and thus to impart the desired oscillation.

The fan is shown provided with a guard 32 of usual character about its blades. In 35 practice, suitable lead-wires are connected with the fan. In the drawings these lead-wires are merely indicated diagrammatically, to enable their general course to be traced. A suitable switch is provided for 40 controlling the electric current which drives the fan. In this instance, such switch is indicated at 33, Fig. 1, located at the bottom of one end of the machine. The plunger 330 thereof is arranged to be depressed by a 45 finger 34 upon the pedal rockshaft 35 to close the switch and let the current flow only when the warping machine is running on high speed.

With the switch arranged to be actuated 50 from the pedal shaft as just described, the blower is automatically set in action and commences to oscillate as soon as the warping machine is put on high speed. At the same time, it is traversed across the width

of the machine, so that the current of air 55 is directed progressively to the whole width of the series of yarns or threads.

What is claimed as the invention is:—

1. The combination with means for guiding and feeding a series of yarns or threads 60 side by side, of a track extending transversely across the width of the said series, a blower mounted upon the said track and movable lengthwise of the latter, and means for moving the blower across the series of 65 yarns or threads comprising a travelling endless cable or belt paralleling said track and operatively connected with the said blower, and supporting pulleys for said cable or belt located at opposite ends of the 70 track.

2. The combination with means for guiding and feeding a series of yarns or threads 75 side by side, of a track extending transversely across the width of the said series, a blower mounted upon the said track and movable lengthwise of the latter, and means for moving the blower across the series of 80 yarns or threads comprising a travelling endless cable or belt paralleling said track and operatively connected with the said blower, and supporting pulleys for said cable or belt located at opposite ends of the track, said belt adapted to slip around said 85 pulleys to permit manual shift of the blower relative to yarns or threads below the same.

3. In warping machines and the like, a blower, a carriage therefor, a track upon which said carriage is movable, an endless belt paralleling said track, and connecting 90 means causing the blower to follow the belt back and forth across the machine, said connecting means permitting a limited amount of manual shifting of the position of the blower along the track independently 95 of the belt.

4. In warping machines and the like, in combination, a blower mounted for traversing movement across the machine, an endless belt, means for driving the same and a 100 flexible connecting link between the blower and the endless belt to cause the blower to move in unison with the belt, said link permitting manual adjustment of the blower without movement of the belt.

MARSHALL F. CUMMINGS.
NATHAN G. LAPHAM.
